Attorney

UNITED STATES PATENT OFFICE

KARL MEYER, OF NEW YORK, N. Y.

COMBINATION ASH TRAY AND CIGARETTE EXTINGUISHER

Application filed March 21, 1932. Serial No. 600,309.

This invention relates to a combination ash tray and cigarette extinguisher.

One of the features of the invention resides in a smoker's article by which lighted cigarettes and stubs placed in an ash receptacle may be readily extinguished to prevent smoldering and to eliminate the necessity of the user rubbing or pressing the lighted end against the bottom of the receptacle while holding the same in the fingers.

Another feature of the invention is to provide a combination article which embodies an ash receptacle and a tamper member or pestle which is captively associated with the receptacle and normally supported by a holder mounted thereon. By reason of the convenient location of the tampering member, the same is readily accessible when needed.

A further feature of the invention is the provision of a cigarette extinguisher which includes a flexible element to one end of which a tamper member is connected, while the opposite end is fixedly attached to a spring actuated winding reel whereby the reel permits of the paying out of the cable during use of the tamper, but automatically causes the rewinding of the cable when the tamper is released after use.

A still further object is the provision of a combination ash receptacle and cigarette extinguisher which is novel and inexpensive of construction, and attractive in appearance.

With these and other objects in view, the invention resides in the certain novel construction, combination and arrangement of parts, the essential features of which are hereinafter fully described, are particularly pointed out in the appended claim, and are illustrated in the accompanying drawing, in which:

Figure 1 is a perspective view of my combination ash receptacle and cigarette extinguisher.

Figure 2 is a vertical longitudinal sectional view showing the position of the cigarette extinguisher in dotted lines when in use.

Figure 3 is a detail vertical transverse sectional view on the line 3-3 of Figure 2.

Referring to the drawing by reference

characters, the numeral 10 designates my improved combination article in its entirety, which includes an ash receptacle 11 which in the present instance is shown in the form of an ash tray, although the same may constitute the top of an ash stand. The receptacle 11 comprises a base 12 having an extension portion 13 projecting therefrom and which serves as a support for a holder or pedestal 14 which rises upwardly from the base 12. The pedestal 14 may be fixedly connected to the extension portion 13 of the base by any suitable means, but in the present instance, I have shown bolts or screws 15 extending through the under side of the extension portion 13 and threaded into the side of the pedestal 14.

An annular recess or cavity 16 is provided in the base, and due to the construction shown in the drawing, a portion of the cavity extends into the pedestal 14 and it is because of the insertion of the reel 17 into the cavity 16 that the pedestal and base are formed of two separate parts. The reel 17 is rotatably mounted upon a stub shaft 18 journaled in the walls of the recess while fixed to the said shaft is one end of a coil spring 19, the opposite end of the said spring being fixed to the reel 17. The convolutions of the coil spring 19 are such as to cause the spring to impart a winding rotation to the reel when the said spring is under tension.

The pedestal 14 rises upwardly from the base and terminates in a bifurcation or seat 20, while opening onto the seat and extending through the pedestal is a passage 21 which also opens into the recess 16.

Fixed to the reel 17 is one end of a flexible element in the form of a cord or cable 22, while the free end of the cord extends through the passage 21 and carries pestle or tamper member 23. The member 23 includes a base 24, a shank 25 and a manipulating head 26. Due to the winding tendency of the spring 19, the cable 22 is windable upon the reel 17 which causes the tamper member 23 to abut the seat 20. The shank 25 of the tamper bears against the seat while the head 26 rests upon the top of the pedestal with the base 24 depending therefrom.

Assume that a lighted cigarette stub such as shown at A in Figure 2 is deposited into the receptacle 11, and it is desired to extinguish the same. The user grasps the head 26 of the tamper 23, and pulls outward upon the cable 22 which causes the unwinding of the cable from the reel 17, but which unwinding movement causes the winding of the coil spring 19. After unseating of the tamper member 23 and the pulling out upon the cable 22, the operator proceeds to press the base 24 of the tamper against the lighted end of the cigarette which has been deposited in the receptacle 11, and by pressing downward thereon causes the lighted end of the cigarette to be smothered, and consequently extinguished. After an extinguishing operation, the user releases the member 23 whereupon the spring 19 rewinds the payed out portion of the cable 22 and causes the tamper member to again seat itself upon the holder or pedestal 14.

From the foregoing description, it will be seen that the practice of extinguishing the lighted ends of cigarette stubs by rubbing the same against the bottom of an ash receptacle is dispensed with and the hands of the smoker are not soiled by the use of my device. The tamper member is captively associated with the ash receptacle so that it is impossible for the same to become separated therefrom. The tamper is always accessible for use when desired.

While I have shown and described what I deem to be the most desirable embodiment of my invention, I wish it to be understood that various changes as come within the scope of the appended claim may be resorted to if desired.

Having thus described the invention, what I claim as new and desire to secure by Letters Patent is:—

A smoker's article comprising in combination, an ash receptacle having a base, a pedestal rising from said base, a seat provided on said pedestal, said base having a recess therein, a reel journaled in said base and disposed within said recess, said pedestal having a passage leading from said recess and opening through said seat, a flexible element having one end fixed to said reel and freely extending through said passage, a tamper member fixed to the other end of said flexible element, and spring means acting upon said reel to wind said flexible element thereon and cause said tamper member to engage said seat.

In testimony whereof I affix my signature.
KARL MEYER.
